UNITED STATES PATENT OFFICE.

HENRY H. PORTER, JR., OF CHICAGO, ILLINOIS.

ICE-HANDLING MACHINERY.

SPECIFICATION forming part of Letters Patent No 761,320, dated May 31, 1904.

Application filed September 5, 1901. Serial No. 74,456. (No model.)

To all whom it may concern:

Be it known that I, HENRY H. PORTER, Jr., a citizen of the United States of America, residing at Chicago, Cook county, Illinois, have 5 invented certain new and useful Improvements in Ice-Handling Machinery, (Case A,) of which the following, taken in connection with the accompanying drawings, is a specification.

This invention has reference to the provision of certain novel and improved devices for the handling of ice, and particularly for the handling of ice where it is to be stored or placed in refrigerating cars, and has for its 15 object primarily to effect economy in the operation of handling the ice, and also to greatly facilitate the said operation, whereby considerable saving in time is effected, and it is not necessary to detain the cars in transit as is 20 the case where present methods are employed.

The above, as well as such other objects as may hereinafter appear, are attained by means of a construction which I have illustrated in preferred form in the accompanying drawings, 25 in which

Figure 1 is a partial elevation of two ice-houses placed near together, with a portion of the mechanism employed in connection with my elevation between them,

Figure 2 is an elevation partly in section, showing the mechanism for elevating the ice, and some of the other parts of the construction, and

Figure 2^a is a view showing the devices related to a support which I employ for the delivery chute,

Figure 3 is a plan view partly in section, showing the tops of a couple of refrigerating cars in a position to be iced,

Figure 4 is a section on the line 4 of the Figure 5, showing a portion of the elevating mechanism, and

Figure 5 is a section on the line 5 of the Figure 4, showing another detail of the elevating construction.

Figures 6, 7, 8, show an ice crusher that may conveniently be used; Figures 7 and 8 being in section, and showing two forms of the crushing roller.

Referring now more particularly to Figures

1, 2, and 3, it will be seen that between two adjacent ice-houses 6 and 7, I have arranged an elevating mechanism 8, comprising an endless chain to which are attached elevating prongs or shelves 9, for carrying the ice, and which is driven by means of some suitable motor, as an engine 10, and terminates at the upper end at a delivery shaft 11, where the ice, if it be in large chunks, is discharged into a crusher 12, and from thence, after being 60 crushed, passes through the chute 13 into the storage hopper 14, from which it is free to pass through the delivery spout 15, when the gate or slide 16 is opened into a car 17 set with the opening therein immediately under the delivery spout 15. The delivery spout is mounted on rollers 18, carried by a pivoted bracket 18^a, (see Fig. 2^a) in a manner which will permit a movement thereof in any direction sufficient to bring it over the opening in the tops 70 of the cars, in case the cars are not spotted upon the track in exactly the right position, and two adjacent hoppers are spaced sufficiently far apart to permit the delivery spout to be moved into position such as will allow 75 the icing of both ends of one car and the ends of the cars adjacent thereto, without respotting the cars.

In order to protect the storage hoppers or bins 14 from extreme temperatures, as well 80 as to facilitate construction, I have located them within the ice-houses.

In order to deliver the ice from the houses to the elevating mechanism 8, I have arranged alongside of each house, a suspended chute 85 or incline 22, which may be raised or adjusted at any desired angle, in any preferred manner, so as to permit the ice to slide down by the action of gravity, and on to the shelves of the elevating mechanism.

As a convenient means of driving the crusher 12, I have provided a belt or chain connection from the crusher to the head shaft 11, whereby the crusher can be driven from the head shaft, but other means could be provided if desired. As shown in Figures 6, 7, 8, the chain 23 engages the sprocket 24 and by means of gears 25, drives the toothed rollers 26 inside the body 12 of the crusher, which is supported on beams 27.

The operation of my invention is as follows. Ice being delivered through the incline or chute to the elevator, as shown at "a" in Figure 2, is carried upward by said elevator and discharged into the crusher 12. Here it is broken up into smaller pieces, and delivered through the trough or chute 13 into the storage bin 14, ready to be discharged into the cars. The cars are run alongside the ice-houses in the position shown, and when the openings in the roofs thereof come nearly under the spouts 15, the latter are adjusted exactly in the right position, and the gates or sliding mechanism 16 opened, permitting the small pieces of broken ice in the storage bin 14 to run down of their own weight into the cars, thus icing the same in a very short space of time, and at a minimum expense, both of time and labor.

From the above it is evident that if the ice provided for use in connection with my invention, be of a divided character, as for example, in small pieces such as may be manufactured artificially, it would not require the use of a crusher 12, but the storage bin 14 could be filled directly, and utilized in the same manner as explained by me.

If desired, salt may be mixed with the ice at any stage of the process, by feeding it to the ice from a source of supply. For this purpose I have shown a salt hopper at 19, with a controlling device at 20, the feed in this case being by gravity controlled by a gate, although other means might be used if preferred.

The specific construction of the feeding chute and bin herein used, I have not claimed in this application; but the same is the subject of my divisional application No. 127,749, co-pending herewith.

Having thus described my invention, what I claim as new, and desire to secure by Letters Patent, is—

1. The combination with a means for elevating and breaking ice, of a hopper for temporary storage of broken ice, and an universally adjustable chute for feeding the broken ice by gravity into a receiving car, substantially as described.

2. In ice handling machinery, the combination with a bin for storing ice in a divided or broken condition, of a delivery chute projected into position to deliver the said broken ice directly into a receptacle requiring to be 45 50 55 iced, mechanism for elevating the ice to said bin, and mechanism for crushing the ice before it is supplied to said bin, substantially as described.

3. The combination with an elevator and means for crushing ice, of a temporary storage bin and an universally adjustable chute for feeding ice from the bin into a receiving car.

4. In ice handling machinery, the combination with means for supplying ice in a divided or broken condition, of an elevated 65 70 75 hopper and a plurality of chutes spaced apart so as to deliver said ice to openings in a plurality of refrigerating vehicles in line without requiring respotting thereof, substantially as described.

5. In ice handling machinery, the combination with a delivery chute projected into position to deliver ice in a suitably divided or broken condition, into a refrigerating vehicle, of means for breaking and feeding 75 broken ice into said chute, and a feeding hopper emptying therein for mixing salt or other substance with the ice, substantially as described.

In testimony whereof I have hereunto set my hand in the presence of two subscribing witnesses.

HENRY H. PORTER, JR.

In presence of—

PAUL SYNNESTVEIDT,
PAUL CARPENTER.
